UNITED STATES PATENT OFFICE.

FRANK S. ALIANO, OF NEW YORK, N. Y.

LOCK.

No. 873,481.

Specification of Letters Patent.

Patented Dec. 10, 1907.

Application filed November 29, 1905. Serial No. 289,547.

To all whom it may concern:

Be it known that I, FRANK S. ALIANO, a citizen of the United States, residing at the borough of Brooklyn, in the city of New York, county of Kings, and State of New York, have invented certain new and useful Improvements in Locks, of which the following is a specification, reference being had therein to the accompanying drawings, 10 which form a part thereof.

My invention relates to locks and more particularly to a class of trunk locks employing a swinging hasp.

The main object of the invention is to provide a lock of this character wherein the operative parts will be compactly arranged and of a design and construction which will permit of the production of the lock cheaply without sacrificing its strength and durability. 20

A further object is to provide a lock employing a rotary bolt controlling plate which will inclose the bolts and be supported from the bottom of the cup.

25 A further object is to provide in a lock a bolt controlling plate which may be stamped from and formed of a single thickness of sheet metal, and yet provide a suitable key seat by means of which the key will be supported free of the bolts and form shoulders to permit the key to rotate or actuate said plate.

A still further object is to provide a lock, the cup of which and the bolt mechanism, 35 will permit of the use of a lock or socket plate capable of being applied to the face of the trunk or chest, or the cover therefor, without boring or cutting an opening therein to receive the lock cup and permit the projection of the bolts beneath said plate.

A still further object is to provide in a lock, a tumbler and tumbler mechanism, which will be so constructed as to give a large range of safety combinations in a small space, thus 45 permitting the use of a lock cup of a small uniform diameter throughout.

A still further object is to provide a bolt and a rotary controlling plate mechanism which will prevent any lateral displacement 50 of the bolts. And a still further object is to provide a lock wherein the coöperating parts of the bolt or bolts and the rotary plate will be so formed as to cause a sufficient throw of the bolt or bolts with a comparatively small 55 quantity of rotation of the plate.

The invention consists primarily in a lock comprising a cup having a bolt opening therein, a sliding bolt seated in said cup and projecting through said opening having a shank provided with a laterally projected abutment, a guide for said shank, a rotary plate carrying a pendent stud adapted to engage said abutment on said bolt, key controlled means whereby said plate may be actuated, a support for said cup, and a lock or socket plate; and in such other novel features of construction and combination of parts as are hereinafter set forth and described and more particularly pointed out in the claims hereto appended. 60

Referring to the drawings: Figure 1 is a longitudinal section of the hasp and the lock or socket plate of a lock embodying my invention showing the cup in elevation; Fig. 2 is a plan view of the cup and its contents detached from its support; Fig. 3 is a plan view of the cup with the tumblers, and tumbler mechanism, the rotary plate, and the key barrel removed, showing the pendent studs of said plate in section, and indicating in 65 dotted lines the position of said bolts and said studs when the bolts are drawn within the cup; Fig. 4 is a section on the line 4—4 of Fig. 2; Fig. 5 is a plan view of the rotary plate; Fig. 6 is a view of a modification of the 70 invention illustrating how with slight change, the lock shown in the preceding figures may be converted into an automatic spring, or snap lock, and Fig. 7 is a view of the form of key used with my improved rotary plate. 75

Like letters refer to like parts throughout the several views.

In the embodiment of my invention shown in the accompanying drawings, A indicates the body of a trunk or chest, and B, the cover 80 thereof. Hinged to the hasp plate C on the part A is a swinging hasp D or other suitable support for the lock cup, the head of which is raised at D' as shown to provide a chamber for the lock cup so as to bring the bottom 85 thereof but slightly below the rim of said hasp, thus preserving the low flat effect generally required in locks of this description, while avoiding such a space under the rim of the hasp as would permit the entrance of a tool 90 thereinto. Secured to the cover B is the lock or socket plate E having a circular opening E' therein. This plate differs from that heretofore employed, however, in that its center 95

portion about said opening is so raised as to provide a space thereunder for the bottom of the lock cup and its bolts, without the necessity for cutting away any part of the cover or lid B.

Permanently secured to the head D' of the hasp D is the lock cup a which is cylindrical and of uniform diameter throughout, with a closed bottom a'. This cup is preferably stamped or pressed up from sheet metal and is formed with integral wings a² adapted to be passed through openings in the hasp and upset to economically unite these parts. Adjoining the bottom a', the cup a is pierced 15 to form bolt openings therethrough at substantially diametrically opposite points.

Mounted on the bottom of the cup a are a plurality of sliding bolts b each comprising a head b' preferably carrying a shoulder b² 20 within said cup shaped so as to engage the wall thereof and limit the amount of projection of the bolt head; and a shank c reduced on the inside as at c' to form a way to permit the bolt to slide past and be guided by the key barrel or stud, and the head of the other bolt, and cut away on the outside, to form the abutment c² and the oppositely disposed and inclined shoulders c³ and c⁴. These shoulders converge toward the center of the 25 cup as shown. The inner ends of the shanks c are rounded to permit them to slide close up to the cup wall, and the adjoining inner corners of each end and of the heads b' are rounded to avoid a collision and binding of 30 the oppositely moving bolts. The bolts are preferably stamped from flat metal stock.

Riveted to the bottom of the cup a at points adjacent to the walls thereof and at points diametrically opposite to each other are the 40 tumbler pivot stud d and the tumbler spring tensioning stud e.

Seated in the cup a is a circular rotary plate f, a section of the edges of which at diametrically opposite points is turned downwardly to form the pendent studs f' adapted 45 to pass between the shoulders c³ c⁴ and actuate the bolts, and support said plate from the bottom a' of the cup and slightly above the bolts b, the spaces left in the periphery of said 50 plate constituting ways for the studs d and e respectively. Said plate carries a tumbler stud f² on its upper face.

It has been my practice heretofore to make plates of this character in two parts riveted 55 together so that by cutting out the metal of the upper plate, the lower plate would form a support or rest for the key, thus permitting the use of stamped plates and avoiding the necessity for machine finishing. To avoid 60 the increased cost due to the increased number of the dies and of the operations necessary in constructing a composite plate as described, I preferably form the plate f of a single thickness of metal, and, excepting those required to bend the studs f' and attach the

tumbler stud f², at a single operation, cutting away a narrow quadrant at f³ concentric with the center of rotation of the plate, to form the way with the shoulders at the ends thereof, necessary to permit the excess movement of 70 the key required to actuate the tumblers prior to the rotation of the plate. The strip f⁴ between the quadrant and the opening for the key barrel or stud, forms the key seat. The tumblers g are mounted on the said plate 75 and to provide a body of metal sufficient to permit such a variance in the width of the tumbler as to give a wide range of combinations for safety, I make them U-shaped with the opening for the bearing whereby it is 80 mounted on the stud d in the bottom thereof. The arms of the tumbler straddle the key barrel or stud, and one arm g' thereof, is imperforate and so arranged as to cover in part the quadrant f³, while the other arm g² is provided with the usual double latch h and the way h' leading therefrom, adapted to engage and permit movement of the stud f² in the usual manner. The tumbler springs i are tensioned by the stud e in the usual manner, 85 and act against the arms g² of the tumblers.

Passing through the center of the plate f and between the shanks c of the bolts b so as to form a guide therefor, is a slotted key barrel j having oppositely disposed shoulders j' j² adapted respectively to engage said plate, and the hasp head D'. The key k is of the ordinary flat variety stepped so as to avoid engagement with the hasp head and impart the proper degree of movement to each tumbler; 95 but is further provided with a downwardly projected finger k' adapted to enter the quadrant f³ and actuate the plate f.

The construction of lock heretofore described, it will be observed, may be locked and unlocked by means of the key only, and this is the preferred form of the invention. In the modification shown in Fig. 6, however, I have illustrated the sole changes required to convert this manually operated lock into an automatic spring or snap lock. Such a conversion does not require an alteration of any of the parts of the lock except the bolts b and the studs f' of the plate f. By cutting away a portion of each bolt head b', 110 I form a spring chamber between the said bolt head and the key barrel j for the springs m, said springs being held in place by the shanks c of the bolts. To permit the necessary action of the bolts independently of the 115 rotary plate f, it is also necessary to make the studs f' thereof narrower than in the preferred form of the invention. The under side of each bolt head would also necessarily be beveled to cause contact thereof with the lock or socket plate opening to actuate the bolts, as indicated in dotted lines at n in Fig. 6. It is also possible that the bolts should be made of thicker metal, and the cup a and socket plate E be drawn to a greater depth 120

to accommodate bolts so increased in thickness, to secure the proper degree of bevel to insure reliability and ease of action.

While I have shown the relation of the 5 quadrant f^3 to the tumblers g to be such as to require the key to be turned from within the tumblers outwardly, it is apparent that this arrangement would be controlled solely by the manner of attaching the lock and the 10 necessity for inserting the key in the barrel in the customary position.

The operation of the preferred form of the herein described lock is substantially as follows, it being assumed that the lock is 15 latched or locked. When so locked or latched it will be observed that the hasp head D' forms a chamber containing the cup a , and that the rim of said hasp incloses and protects this mechanism and the plate E , 20 extending as close to the trunk lid or body as the hasp on the ordinary trunk lock. To withdraw the bolts within the cup a and thus release the hasp, the key k is inserted in the key barrel j until the finger k' thereof 25 enters the quadrant f^3 , the bottom of said key coming to rest upon the strip f^4 which serves as a support for and to steady the key. As the key and the key barrel are turned, the several steps on said key engage their 30 respective tumbler arms g' and rock the tumblers about their pivot stud d to an extent to release the latch h in the arm g^2 and permit the key to pass from the control of said tumblers until the finger k' engages the 35 far shoulder of the quadrant f^3 , whereupon further movement of the key rotates the plate f , the studs f^2 thereof moving in the way k' . Owing to the limited space within the cup a and the necessity for having the 40 dimensions of the shanks c such as to give the required strength of material, it is necessary to give the entire projection of the bolt heads b' and to withdraw them with as little movement of the plate f as is possible. It 45 will be observed that as the bolt studs f' describe an arc, they assume an angular position relative to the shank of the bolt, the rear edge thereof engaging the inclined shoulder c^3 and increasing the direct movement of the bolt over the direct throw of the 50 stud by the quantity of movement represented by the pitch of this incline. This action is due to the simultaneous quantity of movement of the studs f' on a line parallel to the tangent of the arc described at its highest point, and on a line perpendicular thereto, the former of which movements would give a direct movement considerably less than the arc described, and the latter of 55 which, but for the wedge effect produced by the inclined shoulder c^3 or c^4 would ordinarily be lost motion. The pressure from the studs f' is applied simultaneously to the bolts b in two directions at right angles to 60 each other, at any point of the arc described,

one substantially direct movement, and the other changed to a supplemental direct movement by the wedging action aforesaid. It will also be observed that as one edge of said studs f' travels down one incline, the opposite edge travels up the other, thus permitting this increased quantity of movement. This withdraws the bolts entirely within the cup a and permits the hasp D to be raised. To relatch the lock, it is necessary to lower 70 the hasp until the cup passes through the opening E' in the raised central portion of the plate E and is brought to rest by the rim of the hasp D , which position by reason of the raised or bulged head D' brings the bolts 75 b in the proper position to be projected beneath the plate E . Then by rotating the plate f in the opposite direction, the studs f' act against the shoulders c^4 , and operating with relation thereto as above described 80 with relation to the shoulder c^3 , reverses the direction of movement of said bolts. It is apparent that before the hasp can be brought down as described, the bolts b must be withdrawn within the cup a with the key retained in the lock. 85

The operation of the modification shown in Fig. 6 is in the main identical with that of the preferred form of the invention, except that to relatch the lock, it is merely 90 necessary to press the hasp to place, the beveled under surface n of the bolt heads b' serving to force the bolts within the cup a against the tension of the springs m which springs when the bolts have passed beneath 95 the plate E , immediately project the bolts from said cup under said plate, the reduced size of the studs f' permitting this movement of the bolt independently of the plate f . It will be observed that the various working 100 parts within the cup a are so nested as to hold each other in place, and that the hasp head D' confines all these parts, thus avoiding the use of rivets and the resulting loss in time, labor and material. The studs f' resting on the bottom a' , reduces the friction to a very small area, and at the same time, 105 relieves the bolts from the pressure of the plate f . 110

It is not my intention to limit the invention to the precise details of construction herein shown and described, as it is apparent that such may be varied to accommodate the invention to different designs of locks without departing from the spirit and scope of the 115 invention. I believe it to be broadly new to provide a rotary plate stamped from sheet metal with an integral key seat; to provide a U-shaped tumbler substantially as described, to provide a bolt actuated by a rotary plate acting against an incline on said bolt to increase the quantity of projection of 120 said bolt, and to provide a socket or lock plate having a central raised portion to avoid the cutting away of the trunk or chest body 125 130

or cover, and I intend to claim each such broadly.

Having described the invention, what I claim as new and desire to have protected by 5 Letters Patent is:

1. In a lock, a lock cup having a bolt opening therein, a sliding bolt seated in said cup and projecting through said opening having a shank having a way in the side thereof 10 forming a shoulder a laterally projected abutment, a guide for said shank, a rotary plate carrying a pendent stud normally seated in said way and adapted to engage said abutment on said bolt, key controlled 15 means whereby said plate may be actuated, a support for said cup and a lock or socket plate.
2. In a lock, a lock cup having a bolt opening therein, a sliding bolt seated in said cup 20 and projecting through said opening having a reduced shank provided with laterally projected abutments whereby oppositely disposed shoulders are formed, a guide for said shank, a rotary plate carrying a pendent 25 stud seated between said shoulders whereby the rotation of said plate in opposite directions will project or withdraw said bolt, key controlled means whereby said plate may be actuated, a support for said cup, and a lock or socket 30 plate.
3. In a lock, a lock cup having a bolt opening therein, a sliding bolt seated in said cup and projecting through said opening having a shank provided with a laterally projected 35 abutment presenting an inclined shoulder, a guide for said shank, a rotary plate carrying a pendent stud adapted to engage said abutment on said bolt, key controlled means whereby said plate may be actuated, a support 40 for said cup and a lock or socket plate.
4. In a lock, a lock cup having a bolt opening therein, a sliding bolt seated in said cup and projecting through said opening having a reduced shank provided with a laterally projected 45 abutment whereby oppositely disposed shoulders converging toward the center of rotation of the rotary controlling plate, are formed, a guide for said shank, a rotary plate carrying a pendent stud seated between 50 said shoulders whereby the rotation of said plate in opposite directions will project or withdraw said bolt, key controlled means whereby said plate may be actuated a support for said cup, and a lock or socket plate.
5. In a lock, a lock cup having a plurality of substantially diametrically opposite bolt openings therein, a plurality of oppositely sliding bolts seated in said cup and projecting through said bolt openings respectively, 55 each having a shank provided with a laterally projected abutment whereby oppositely disposed shoulders converging toward the center of rotation of the rotary controlling plate, are formed, a guide for said shanks, a 60 rotary plate carrying a plurality of pendent 65 studs at diametrically opposite points thereof seated between said shoulders on said bolts, respectively whereby the rotation of said plate in opposite directions will project or withdraw said bolts, key controlled means whereby said plate may be actuated, a support for said cup, and a lock or socket plate.
6. In a lock, a rotary controlling plate 70 consisting of a single thickness of sheet metal having a central bearing, and a segmental opening therein concentric with said bearing whereby a key support is formed adjacent to said bearing, and a downwardly bent integral section of said plate whereby the rotation of said plate may actuate the bolts of a lock.
7. In a lock, a substantially U-shaped tumbler having a bearing in the bottom thereof, the arms thereof being adapted to 75 straddle the key pin or barrel, one of said arms having a latch opening therein, and the other being imperforate and adapted to cover the key seat or way in the actuating mechanism and to be engaged by the key. 80
8. In a lock, a lock cup having a bolt opening therein, oppositely disposed studs carried by said cup, a bolt in said cup projecting from said opening, a rotary plate, means carried by said plate whereby said bolt may be actuated, a tumbler stud on said plate, a substantially U-shaped tumbler having a bearing in the bottom thereof mounted on one of said studs carried by said cup, the arms of said tumbler being adapted to straddle the 85 key pin or barrel of the lock, one of said arms being imperforate and adapted to cover a key seat or way in said plate, and the other said arm being adapted to engage said tumbler stud on said plate, a spring acting on 90 said last-mentioned arm tensioned by the other stud carried by said cup, a key guide, and a lock or socket plate.
9. In a lock, a lock cup of substantially the same diameter throughout, having a plurality of substantially diametrically opposite bolt openings therein, oppositely disposed studs carried by said cup, a plurality of oppositely sliding bolts seated in said cup and projecting through said openings respectively, each having a shank provided with a laterally projected abutment whereby oppositely disposed shoulders converging toward the center of rotation of the rotary 110 controlling plate, are formed; a rotary plate having a key seat and opposed shoulders thereon, a plurality of pendent studs at diametrically opposite points thereof seated between said shoulders on said bolts, respectively, whereby the rotation of said plate in 115 opposite directions will project or withdraw said bolts, and ways adjoining said last-mentioned studs for the studs carried by said cup, a tumbler stud carried by said plate, a key barrel passing through said plates and 120
10. In a lock, a lock cup having a plurality of substantially diametrically opposite bolt openings therein, a plurality of oppositely sliding bolts seated in said cup and projecting through said bolt openings respectively, each having a shank provided with a laterally projected abutment whereby oppositely disposed shoulders converging toward the center of rotation of the rotary controlling plate, are formed, a guide for said shanks, a 125 rotary plate carrying a plurality of pendent 130 studs at diametrically opposite points thereof seated between said shoulders on said bolts, respectively, whereby the rotation of said plate in opposite directions will project or withdraw said bolts, and ways adjoining said last-mentioned studs for the studs carried by said cup, a tumbler stud carried by said plate, a key barrel passing through said plates and

between said bolts, a substantially U-shaped tumbler having a bearing in the bottom thereof mounted on one of said studs carried by said cup, the arms of said tumbler straddling said key barrel and being adapted to partially cover said key seat and engage a key, and to engage the tumbler stud on said plate respectively, a spring acting on the last mentioned arm, tensioned on the other 10 stud carried by said cup, a support for said cup, and a lock or socket plate.

10. In a lock, the combination with a swinging hasp having a downwardly projected circular flange, or rim on the head 15 thereof, a cylindrical cup having a closed bottom, within said head and having a bolt opening in the side thereof, a bolt adapted to be projected through said opening, and means whereby movement of said bolt is 20 controlled, of a lock or socket plate having a circular opening therein and the portion thereof adjacent to the edge of said opening raised or drawn up so as to be contained within the flange or rim of the hasp; to permit the cup to pass through the opening and 25 to permit the bolt to be projected thereunder and between said lock or socket plate and a trunk or chest.

11. In a lock, the combination with a swinging hasp having the central portion of 30 the head raised, or drawn up and a downwardly projected circular flange or rim on said head, a cylindrical cup having a closed bottom carried below the raised or drawn up portion of the hasp head whereby the cup is 35 contained within the flange or rim of said head, said cup having an opening in the side thereof, a bolt adapted to be projected through said opening, a bolt controlling 40 mechanism within said cup and a lock or socket plate having a circular opening therein and the portion thereof adjacent to the edge of said opening raised or drawn up so as to be contained within the flange or rim of the hasp; to permit the cup to pass through 45 the opening and to permit the bolt to be projected thereunder and between the said lock or socket plate and a trunk or chest.

In witness whereof, I have hereunto affixed my signature, this 27th day of November, 1905, in the presence of two witnesses.

FRANK S. ALIANO.
